FLOOR CLEANER

Walter C. Jerome, Worcester, Mass.

Application May 21, 1936, Serial No. 81,066

6 Claims.

(Cl. 15—9)

The present invention relates to a floor treating machine, and particularly to a machine capable of performing several different operations, such as washing and drying floors and rugs, vacuum cleaning rugs, and waxing and sanding floors.

Up to the present, separate devices have necessarily been provided for each of the several floor treating operations enumerated, and if a home was completely equipped, a large investment was involved in providing the several different devices. The disadvantages of owning and storing a plurality of devices is readily apparent and the principal object of the present invention is accordingly to provide a universally useful device by which a plurality of different floor treating operations can be performed.

In prior devices for use in vacuum cleaning, the dust is separated from the air used in cleaning by passing the air through a filtering bag which must be cleaned frequently or thrown away after use in order to maintain an efficient cleaning action. Cleaning of the bag is not a pleasant task and if the bags are thrown away, a considerable expense is involved in the purchase of new filtering bags. One of the objects of the present invention is to avoid these disadvantages by using a relatively inexpensive filtering medium, the frequent replacement of which will involve almost no expense.

The filtering of the dust from the air in the conventional vacuum cleaner necessitates the passage of air through the filter medium on which the dust is constantly accumulating. Thus, as the filter medium becomes more and more saturated with dust, the cleaning action of the medium is diminished and the air pressure required in forcing air through the medium is increased. A further object of the present invention resides in providing for the collection of dust, which is filtered from the air, in a receptacle separate from the filtering medium, so that the latter remains relatively clean and the air used in cleaning does not pass through a layer of collected dust before it is filtered.

Other and further objects and advantages of the invention will appear from the following detailed description taken in connection with the accompanying drawings, in which—

Fig. 1 is a side elevation of a device embodying the invention.

Fig. 2 is a sectional view on a large scale through a part of the device of Fig. 1.

Fig. 3 is a vertical section substantially along the line 3—3 of Fig. 2.

Fig. 4 is a plan view looking into the dust collector, the cover for the device having been removed.

Fig. 5 is a fragmentary side elevation with parts broken away to show a part of the structure for driving the brush.

Fig. 6 is a fragmentary vertical section showing the movement of air around the brush.

Fig. 7 is a fragmentary section similar to Fig. 6, showing a modification.

Fig. 8 is a sectional view of part of the hinge connection for the device, as along the line 8—8 of Fig. 9.

Fig. 9 is a sectional view through the hinge at right angles to the section of Fig. 8, along the line 9—9 of Fig. 8.

Fig. 10 is a sectional view through a part of the mechanism which drives the brush.

Fig. 11 is a sectional view through one of the brushes.

Fig. 12 is a sectional view showing the attachment of the dust collector to the remainder of the device, the left part being along the line 12—12 of Fig. 6, and the right part being along the line 12a—12a of Fig. 6.

Fig. 13 is a sectional view through the air discharge at the end of the motor, as along the line 13—13 of Fig. 14.

Fig. 14 is a sectional view along the line 14—14 of Fig. 13.

Fig. 15 is a fragmentary sectional view of a modification showing the means for applying water in the washing of floors or rugs.

Fig. 16 is a side elevation of the parts in section of the device of Fig. 15.

Fig. 17 is a side elevation of the structure by which the elevation of the brush above the floor may be controlled.

Fig. 18 is an end view of the structure of Fig. 17.

Fig. 19 is a section through a sanding drum for attachment to the device when sanding floors.

Like reference characters refer to like parts in the different figures.

Referring first to Fig. 1, the device comprises a base 1 supported on a pair of wheels 2 adjacent the front and an adjustable rear wheel 3. Hingedly connected to the base is the cover 4 which extends over the dust collecting device 5 which also has a forward continuation 6 forming a hood for the brushes. A vacuum is provided by an electric motor and fan 7 hinged to the base 1, this motor being of a type which

passes the air directly therethrough, or which passes the air therearound from one end to the other, as for example, the motor and fan arrangement of the Edstrom Patent No. 2,029,613, dated February 4, 1936. A handle 8 is connected to the discharge end of the motor 7 and is hollow to direct air from the motor through the handle and a flexible hose 9 to an air intake 10 on the base of the machine. There is accordingly no discharge of air from the device into the atmosphere of the room since the air which is drawn from adjacent the brushes 11 is carried upwardly through the cover 4 to the fan carried in the housing 1' forming part of the motor 7 and is then discharged through the flexible hose 9 back to the base of the machine where it is directed forwardly, as will herein-after appear, and escapes adjacent to the brush.

Referring now to Fig. 2, the brushes 11 are driven from the motor 7, the projecting shaft 12 of which has a pulley 13 on the end thereof. The pulley 13 is connected to a pulley 14 on the end of a shaft 15 by a belt 16 which is guided by spaced pulleys 17, only one of which is shown, carried by a shaft 17' journaled in a bracket 18 secured to the rear wall of the base 1. The center of rotation of the pulleys 17 coincides with the axis of the hinge connection between the motor 7 and the base, herein-after described in detail, and permits relative movement therebetween. The belt 16, being of rubber, is allowed to stretch to such an extent as to permit the desired movement of the motor. The shaft 15 is mounted in a tube 19 which provides a bearing surface for the shaft adjacent to the pulley 14, the tube being inclined downwardly toward the front of the device, as shown. The forward end of the shaft 15 carries a worm 20 which, as shown in Fig. 10, is in mesh with a worm gear 21 secured to a sleeve 22 journaled in bearings 23 provided by housings 24 and 25 secured to an annular member 26. The member 26 is attached to a transverse member 27, Fig. 2, which is secured to the base 1, said member 27 having a notch 28 centrally thereof to receive the tube 19.

Referring now to Figs. 10 and 11, the sleeve 22 has secured inside thereof a pin 29 having a notch 30 in each end thereof. The brush 31 has an axial recess 32 in one end thereof, in which is located the inner end of the brush shaft 33, the latter projecting through the brush and having a short protruding end 34 on the outside thereof. The inner end of the shaft has a tongue 35 engageable with the notch 30 and the diameter of the shaft 33 is such as to provide a relatively tight fit with the sleeve 22. The brushes are accordingly removable from the device to provide for the substitution of different types of brushes or of sanding rolls, Fig. 19, and, when in position, are positively driven from the same motor that operates the fan to provide the desired suction. Bristles 36 are suitably attached to the brush and are of a sufficient length to extend downwardly below the lower edge 37 of the base.

The height of the brush above the floor is adjusted by raising or lowering the rearward edge of the base. As above stated, the base is supported adjacent its front end by rollers 2 on opposite sides of the base, said rollers being carried by brackets 38 secured to said base in back of the brush support. As best shown in Figs. 17 and 18, the rearward wall of the base 1 has projecting webs 39 in which is journaled a shaft 40, the left hand end 41 being offset and carrying a threaded adjusting screw 42. The latter passes through

5 a lug 43 on the side wall of the base and is engaged by an adjusting nut 44. The shaft 40 carries spaced parallel arms 45 supporting a bar 46 on which is journalled the rear roller 3, the latter 10 being axially slideable on the bar. Adjustment of the nut 44 will accordingly raise or lower the roller 3 and thereby raise or lower the front end 15 of the device.

Referring now to Figs. 8 and 9, the motor is 20 connected to the base by a hinge construction comprising a brace 47 extending rearwardly from the base and having an opening 48 through the upper end thereof. Although two of these braces are 25 provided adjacent opposite edges of the rear wall, only one is shown, as each of the hinges is a duplicate of the other. For each hinge the cover 4 has a rearwardly extending portion 49 which has an opening 50 in axial alignment with the opening 48, the portion 49 being connected to the cover by a channel 51, through which air may pass. For each hinge the lower end of the fan housing 1' has a downwardly extending portion 52 which is hollow and has a cylindrical opening 53 in axial alignment with the openings 48 and 50. A sleeve 54 is positioned within the openings 48, 50 and 53 and has a pin 55 which prevents turning movement of said sleeve relative to the portion 49 of the cover, thereby keeping an opening 56 in the sleeve in alignment with the channel 51. A cap 57 is positioned on the end of the portion 49 to prevent the entrance of air. Accordingly the vacuum set up in the housing 1' by the fans is transmitted through the hinge to the cover, as will be apparent.

30 As best shown in Figs. 2 and 3, the collecting device 5 includes a collecting chamber 58 in the form of a pan, which fits within the base of the device, in back of the member 27, and has an outwardly extending flange 59 at its upper edge which rests on the upper edges of the base. On the upper edge of the flange 59 is a compressible packing 60 engageable with the cover, and a second strip 61 of compressible packing beneath the flange 59 seals the connection between the chamber 58 and the base. The forward edge of the collecting chamber rests on the member 27 and extends therebeyond and over the brushes, the extreme forward end 61' thereof being positioned forwardly of the center of the brush, as shown. Integral with the collecting chamber and forming a part of the collecting device 5 is a hood 62 which extends downwardly in front of the brush and has its lower end 63 substantially parallel to and forwardly of the lower edge of the brush, although preferably spaced slightly thereabove to allow the brush to engage the rug or floor. The end 63 is spaced from the forward edge 37 of the lower wall of the base to provide an opening 64 through which the brush may project for engagement with the floor or rug.

60 The hood 62 extends rearwardly above and in spaced relation to the end 61' of the collecting chamber and the rearward edge of the hood 62 is located horizontally beneath the forward edge of the cover 4 with a portion of the packing 60 resting thereon. As shown in Fig. 12, the opposite side walls 65 of the hood 62 extend downwardly to form a closure for the ends of the compartment in which the brushes are located and engage with the outwardly extending ends 34 of the brushes to prevent either of the latter from being accidentally moved out of operative position. The side walls 65 carry narrow plates 66 which are in alignment with the opposite ends of the transverse member 27 to provide a tight en-

gagement between the hood and said member. The plates 66 are held away from the side walls 65 by resilient packing 68' which allows the plates 66 to move slightly in accommodating the hood to the remainder of the device. It will be apparent that when the cover 4 is swung upwardly out of operative position, the collecting device 8 may be removed as a unit, since it is not permanently attached to the base, thus providing for emptying the collecting chamber.

The cover has a horizontal screen 67 secured therein, as by the cleats 68, to form a support for a web of filtering material 69, such as felt, or other substance suitable for the purpose. This filtering material corresponds in area substantially to the area of the cover and the outer edges thereof are clamped between the cover and the packing 68 when the cover is closed. The vacuum created in the cover by the suction motor results in a movement of air through the opening 64 upwardly in front of the brushes and through the space between the plate 61 and hood 62 into the collecting chamber. From the hood the air passes upwardly through the filtering material which removes the dust and dirt therefrom. As the dust will not adhere in large quantities to the underside of the filtering material it drops off and is collected in the collecting chamber from which it can be removed at any time by raising the cover and removing the collecting device.

As shown in Fig. 1, the cover is normally held in closed position on the device by clamps 70 on opposite sides thereof. Each clamp comprises a clamping screw 71 pivoted on a lug 72 extending outwardly from the side wall of the base. The clamping screw projects through a notched lug 73 on the cover, and an adjusting nut 74 on the clamping screw permits adjustment of the cover and release thereof for opening the device.

The air passing through the device goes around the brush and through the passage way between the forward end 61' of the collecting chamber and the hood 62 into the collecting chamber. From the chamber the air passes through the filtering medium and the hinges to the fan and is then discharged selectively through the hollow handle 8 or through ports at the end of the motor and fan unit. As best shown in Figs. 13 and 14, the end of the motor and fan has secured thereto a hood 75 having ports 76 on opposite sides thereof. Within the hood is positioned a plate 77 having a tapered bore 78 to receive the tapering end of the handle 8 and having spaced flanges 79 in a position to cover the openings 76 when the plate is in the proper position. As shown in Fig. 13, the plate 77 may be turned to a position for uncovering both of the openings 76 to allow discharge of the air into the atmosphere, at which time the end of the handle 8 is closed by a pivotally mounted cover 80 carried by a pin 81 in a boss 82 projecting from the end of the motor. The cover 80 has a slot 83 engageable with a pin 84 secured to the plate 77 and turning movement of the plate 77 to close the openings 76 will procure a corresponding swinging movement of the cover 80 to uncover the end of the handle 8. The plate 77 is held in proper position within the hood 75 by engagement between the flanges 79 and the end of the motor housing.

The tapered handle end is held resiliently within the bore 78 by a spring pressed ball 77' engaging with a recess 78' in the handle. The plate 77 is resiliently held against turning by a spring pressed plunger 75' located in the hood 75 and 75'

engageable with either of two recesses 78' in the plate 77. These recesses 78' locate the plate 77 with the openings 76 selectively fully open or entirely closed.

As above stated, the device is adapted to the cleaning of walls or furniture by the removal of the handle 8 from engagement with the plate 77 and the positioning of small cleaning implements on the end of the handle. In order to obtain the desired suction at the end of the handle when using the device for cleaning in this manner, a plate 85, Fig. 6, is mounted to be swung into the opening through which the brush normally engages the floor. The plate 85 is arcuate, as shown in Fig. 6, and has projecting ears 86 at opposite ends thereof for engagement with pins 87 in the depending side walls 65 of the hood. These pins 87 are positioned above the axis of rotation of the brushes so that the plate when swung downwardly into a position to close the cleaning opening will engage the ends of the bristles of the brush and at the same time will extend entirely across the opening, as shown in full lines in Fig. 6. One of the pins 87 has an arm 88, Fig. 12, on the outer end thereof with a spring pressed plunger 89 on the end of the arm to hold the plate against swinging movement. The arm provides a means for turning the plate from the position shown in Fig. 6 to that of Fig. 12, in a position vertically above the brush and directly beneath the plate 61', in which position the plate 85 is entirely inoperative.

When the device is used for cleaning and drying floors or rugs the plate 85 is swung to the position of Fig. 7 forwardly of the brushes and with the upper edge of the plate engaging with the forward end of the plate 61', the position being shown in dot-dash lines, Fig. 6. In this position, the plate 85 provides a relatively narrow orifice 90 which directs a sufficient vacuum to the opening through which the brush engages the floor to assure the removal of water therefrom. In the washing of floors the forward end 63 of the hood has attached thereto a plate 91 having a squeegee 92 on the lower edge thereof. The plate 91 is held in position by spring clips 93 and the rubber squeegee 92, which engages the floor as the cleaner is moved over it, removes any excess water from the floor.

When the device is used for floor or rug washing or drying, a supply of water is placed in the collecting chamber 58 from which it is drawn by the mechanism shown in Figs. 15 and 16. With reference to these figures, the rear wall of the collecting chamber has an opening 94 through which a pipe 95 projects, the latter having a right angle bend therein so that the end of the pipe is located adjacent to the bottom wall of the collecting chamber. The end of the pipe outside of the collecting chamber is connected to a second pipe 96 by a suitable joint 97 which permits turning movement of the pipe 96. The pipe 96 is bent substantially centrally at a right angle and the end of the pipe 96 has secured thereto a cup 98 having a small opening 99 therethrough adjacent to the opening in the end of the pipe. The cup 98 is positioned in a vertical passage way 100 provided by the connecting member 10 and as air passes from the hose 9 into the member 10 the pressure of the air against the cup 98 swings the pipe 96 from its normal or dotted line position of Fig. 15 into the full line position of that figure. Air passing through the opening 99 creates enough of a vacuum at the end of the pipe 96 to draw water from within the collecting chamber and direct it beneath said chamber.

to the brushes. As soon as the air supply through the hose 8 is cut off by stopping the motor, the pipe 96 is again returned to the dotted line position of Fig. 15, as by a spring 101, to prevent discharge of water from the collecting chamber while the device is inoperative.

From the foregoing it will be apparent that the device is useful as a floor cleaner and washer, and also as a rug washer, as well as being adapted for use in cleaning furniture or the walls of a room where a small portable cleaning tool is desirable.

The device may also operate as a sander by the substitution of the sanding drums of Fig. 19 for the brushes shown in the other figures. With reference to this figure, the sanding drum comprises a cup shaped element 102 having a spindle 103 extending through the base thereof. The cup is large enough to extend over the sleeve on the members 24 and 25, and the spindle has a tongue 103' corresponding to the tongue 35. The edge of the cup has a projecting flange 104, and surrounding the cup are rubber annuli 105. Rubber disks 106 surround the spindle 103 outside of the cup and the nut 107 on the threaded end of the spindle engages with a washer 108 for compressing the rubber disks and annuli. Compression of the disks by tightening the nut expands them to fit tightly within a cylinder of sanding paper 109. Two of these sanding disks are provided, and the suction produced by the fan picks up the dust from the sanding operation and collects it all in the collecting chamber.

The sanding disk, or the brush, rotates with the surface engaging the floor moving toward the portion 63 of the hood so that the periphery of the disk, or brush, is moving in the same direction as the air being blown onto and drawn from the floor. The nozzle which directs the air onto the floor is located adjacent to the floor and directs the air substantially tangentially of the brush periphery, with the brush moving in the same direction as the air blast. In order to assure a uniform distribution of the air under pressure from the discharge side of the fan to the brush, where it engages the floor, the space between the bottom of the collecting chamber 58 and the base 1 is relatively narrow and shaped to provide a nozzle by the positioning of suitable packing material 110, which, as best shown in Fig. 4, is so located as to provide a continuously increasing area for the passage of the air from the entrance 10 to a point adjacent its discharge against the brushes. It will be obvious that the member 21 also aids in forming a nozzle arrangement by having its lower edge spaced above the bottom wall of the base 1 over the greater portion of its length, as indicated in Fig. 1, this spacing providing slots 111 through which the air is directed.

I claim:

1. In a vacuum cleaner, a base, a removable collecting chamber positioned in the base, said base and chamber defining a suction opening adapted to be closely spaced from the surface being cleaned and a passage from said opening to the chamber, a cover hingedly mounted on the base and a filter member located above the collecting chamber and held in position by said cover, a fan hingedly mounted on the base, and means providing for passage of air from the cover to the fan through both hinge connections.

2. In a vacuum cleaner, a base, a collecting chamber having a collecting pan within the base,

said base and chamber defining a slot adapted to be closely spaced from the surface being cleaned and a passage from said slot to the pan in the chamber, a cover positioned above the collecting chamber, a filtering member positioned between the collecting chamber and cover, a fan connected to the cover for applying suction to the inside thereof, a rotary brush carried by the base and engageable with the floor through the slot, and means for directing water from within the collecting chamber to the brush when the fan is in operation, said last means including means for directing the exhaust air from the fan to the brush adjacent its periphery thereof, and means controlled by the blast of air for removing water in the form of a spray from the collecting chamber.

3. In a vacuum cleaner, a base, a brush carried by said base and engaging with the floor, a collecting chamber positioned within the base and having an integral shield extending over the brush to define with the base a narrow slot through which the brush extends, said base and chamber defining a passage from the slot to the collecting chamber, a fan for providing a suction in the collecting chamber, a connection from the discharge side of the fan to the base for directing the discharged air to the brush adjacent the slot, and a pivotally mounted shield adapted to be moved into position to close the slot.

4. In a vacuum cleaner, a base, a brush carried by said base and engaging with the floor, a collecting chamber positioned within the base and having a shield extending over the brush to define with the base a narrow slot through which the brush extends, and a pivotally mounted shield adapted for swinging movement to close said slot.

5. In a vacuum cleaner, a base, a collecting chamber having a collecting pan within said base, said collecting chamber and base defining a slot adapted to be closely spaced from the surface being cleaned and a passage from said slot to the collecting pan, a fan for providing suction in the collecting chamber, a filtering member between the collecting chamber and the fan, a hollow handle connected to the discharge side of the fan and a pneumatic connection from the handle to the base, said handle being releasable from the fan for use as a cleaning member, said base having a channel providing a passage for air from the point of attachment of said connection and the base to the slot through which the cleaning action takes place.

6. In a vacuum cleaner, a base adapted for movement over a surface being cleaned, a collecting chamber within the base and forming with said base a slot and passage through which suction is normally directed to the floor for cleaning, a fan having its suction side connected to the collecting chamber, a filter between the chamber and the fan, a flexible connection from the discharge side of the fan to the base for directing the discharged air to the cleaning slot in the base, said flexible connection being releasable from the

60 discharge side of the fan, and means for closing the slot in the base so that the suction normally applied at said slot will be applied at the end of the flexible connection, said base and collecting chamber defining a channel within the base which provides a connection between the cleaning slot and the connection from the discharge side of the fan.

WALTER C. JEROME.
